UNITED STATES PATENT OFFICE.

LOUIS GOHLKE, OF GRAND RAPIDS, MICHIGAN, ASSIGNOR TO T. STEWART WHITE, THOMAS FRIANT, GAIUS W. PERKINS, AND CHARLES J. REED, OF SAME PLACE.

DESIGN FOR A CARPET-SWEEPER CASING.

SPECIFICATION forming part of Design No. 24,365, dated June 4, 1895.

Application filed September 14, 1894. Serial No. 523,041. Term of patent 7 years.

To all whom it may concern.

Be it known that I, LOUIS GOHLKE, a citizen of the United States, residing at Grand Rapids, in the county of Kent and State of Michigan, have invented a certain new and original Design for Carpet-Sweeper Casings, of which the following is a specification.

This design relates to a carpet sweeper casing and the distinctive features consist in a raised middle panel, two intermediate side panels, in parallel planes with and below the plane of the middle panel and two inclined outer panels having ogee surfaces; said panels being divided by four distinct lines of carved quarter rounded moldings, the whole shaped and ornamented to form the casing as fully illustrated in the accompanying drawings, in which—

Figure 1 is a plan view of a carpet-sweeper casing embodying my design, and Fig. 2 an end elevation of the same.

Like letters refer to like parts in both of the figures.

A represents the middle panel arranged in a horizontal plane and having quarter round 25 carved edges A', A' as shown.

B, B, represents the side panels, having their upper surfaces in the plane of the under surface of the middle panel A, and their inner edges beneath the same, and their outer edges 30 B' B' quarter round and carved as shown.

C, C, are the outer side panels arranged at an inclination of substantially forty-five degrees, and having their upper edges beneath the outer edges of the intermediate panels B, 35 B, and their surfaces concavo convex, or ogee as shown.

What I claim is—

The design for a carpet sweeper casing, substantially as herein shown and described. 40

In testimony whereof I affix my signature in presence of two witnesses.

LOUIS GOHLKE.
